UNITED STATES PATENT OFFICE.

CHARLES F. CRAMER, OF INDIANA, PENNSYLVANIA.

SHARPENING APPLIANCE.

1,274,513.

Specification of Letters Patent. Patented Aug. 6, 1918.

Application filed April 8, 1918. Serial No. 227,322.

To all whom it may concern:

Be it known that I, CHARLES F. CRAMER, a citizen of the United States, residing at Indiana, in the county of Indiana and State 5 of Pennsylvania, have invented certain new and useful Improvements in Sharpening Appliances, of which the following is a specification.

This invention relates to devices for 10 sharpening knives and like purposes, and the general object is to provide a device of this character using a sheet of abrading material, the device being formed to provide a support for the abrading material, and rollers 15 upon which the abrading material may be wound, so that by rotating one of the rollers the abrading material may be shifted to bring a new surface into position for use.

A further object is to provide a construction 20 of this character embodying an elongated supporting member, rollers supported below the supporting member and upon which the abrading material is wound, the rollers being provided with means whereby 25 they may be restrained or held from accidental rotation, which would tend to slacken the sheet.

A further object is to so mount the rollers 30 as to keep the abrasive fabric taut and free from wrinkles, due to unequal buckling of the fabric.

A further object is to provide improved 35 means for attaching the abrading fabric to the rollers so that the abrading fabric may be readily removed from the rollers or replaced thereon.

Other objects will appear in the course 40 of the following description.

My invention is illustrated in the accompanying drawings, wherein:

Figure 1 is a perspective view of my improved sharpening device;

Fig. 2 is a vertical longitudinal section 45 of the handle end of the sharpening device; and

Fig. 3 is a section on the line 3—3 of Fig. 2.

Referring to these drawings, it will be seen that my sharpening device comprises 50 a fabric supporting body 10, which may be made of wood, composition, or any other suitable material, and which has a rounded upper face and rounded corners. This body 10 is supported at one end by a plate 11, 55 which is preferably of metal, though it may be made of other material, this plate con-

stituting a support, while at the opposite end of the body 10 there is attached the plate 12, which is also preferably made of metal and constitutes a support. The plates 11 60 and 12 may be held to the body 10 by means of screws or in any other suitable manner. Preferably the plate 12 upon its inside face, below the body 10, is cut away, as at 13, and attached to the plate 12, or preferably 65 formed as an integral part of the body 10, is a handle 14.

The plate 11 is formed with the perforations 15, while the plate 12 is formed with upwardly divergent, elongated perforations 70 or slots 16. Disposed through these slots 16, and rotatably disposed in the perforations 15, are the winding shafts 17, which terminate with knobs at their ends below the handle 14 and mounted upon each shaft 17 75 is a sleeve 19, which may be made of metal, wood, composition, or of any other suitable material, but which is preferably of thin metal, this sleeve being screw-threaded, as at 19^a. Coacting with the sleeve is a collar 80 20, which is interiorly screw-threaded to engage the screw-threads 19^a and which constitutes a nut. This collar is preferably formed with a band 21, which band may be knurled or may be made of rubber or other 85 material with which the finger can readily engage.

Passing through each shaft 17 is a pin 22, which bears against the inside face of the member 12 when the corresponding collar 90 20 is turned up, so that the wall of the opening 16 is clamped between the collar 20 and the pin 22, when it is desired to hold the roller or shaft from rotation. It will be understood, of course, that the sleeve 19 95 is to be pinned or otherwise attached to the corresponding shaft or roller, so as to rotate therewith. By rotating the collar 20 reversely, it is released from its engagement with the wall of the perforation 16 and this permits the roller to be rotated freely and by removing the pin 22, it is obvious that the roller or shaft may be entirely removed.

While I do not wish to be limited to any particular means for holding the abrading 105 sheet or fabric upon the rollers 17, I have shown each of these shafts as being formed with the longitudinally extending grooves 23, connected by transverse bores 24, a lace 25 being threaded through these grooves 23 110 and bores 24, this lace being passed through suitable openings in the margin of the sheet

18 and holding the ends of the sheet in firm engagement with the roller or shaft. By this means the sheet 18 may be held at its ends attached to the shafts 17 along its entire extent and it is obvious that the sheet 5 may be readily disengaged and a new sheet engaged with the shafts whenever it is necessary to replace the worn out abrading sheet with a new one.

10 The use of my invention will be obvious from what has gone before. Ordinarily that portion of the sheet which is extended over the sides and curved upper face of the supporting member 10 will constitute the abrading 15 surface, and the knives, scissors, or other article desired to be sharpened will be drawn across this abrading sheet. When the sheet has become so worn as to be of no further value, the collars 20 are released and the 20 rollers or shafts 17 rotated in a direction to wind up the used portion of the sheet on one of the shafts and bring a fresh portion of the sheet over the upper surface of the body 10. The collars 20 then may be turned 25 up again to hold the shafts from further accidental rotation. The object of providing the inclined slots 16 for the handle ends 30 of the shafts is to permit the rollers to be forced downward, to thereby tighten the abrading fabric over the form 10. It will be noted that the member 12 constitutes a hilt 35 guard, which will prevent knives being sharpened from cutting the hand, thus permitting the device to be used without extreme care being taken.

While I have illustrated a form of my invention which I regard as particularly effective in use and which may be cheaply made, yet it will be understood that many 40 modifications may be made in the details of construction and arrangement of the parts without departing from the spirit of the invention, as defined in the appended claims.

Having described my invention, what I 45 claim is:

1. A sharpening device of the character described comprising an elongated body having a rounded upper face and rounded corners, supporting members disposed at opposite ends of the body and extending below it, a handle extending from one end of the body, rollers rotatably mounted in the supporting members and disposed beneath the body and extending through the supporting 55 members, a sheet of abrasive material extending over the top of the body and wound upon said rollers, and means on the rollers disposed beneath the handle for holding them against accidental rotation constituting 60 means whereby the rollers may be rotated.

2. A sharpening device of the character described comprising an elongated body having a rounded upper face and rounded corners, supporting members disposed at opposite ends of the body and extending below

it, rollers rotatably mounted in the supporting members and extending below the body, a sheet of abrasive material extending over the body and wound upon said rollers, and means on the rollers for holding them 70 against accidental rotation, said means including a nut having screw-threaded operative engagement with a roller and adapted to be turned to bear against the adjacent supporting member.

3. A sharpening device of the character described comprising an elongated body having a rounded upper face and rounded corners, supporting members disposed at opposite ends of the body and extending below it, rollers rotatably mounted in the supporting members and extending below the body, a sheet of abrasive material extending over the body and wound upon said rollers, and means on the rollers for holding them 80 against accidental rotation, said means comprising a pin extending through each roller and bearing against the inside face of the corresponding supporting member; and a nut having screw-threaded engagement with 85 the roller and adapted to bear against the outer face of the support.

4. A sharpening device of the character described comprising an elongated body having a rounded upper face and rounded corners, supporting members disposed at opposite ends of the body and extending below it, rollers rotatably mounted in the supporting members and extending below the body, a sheet of abrasive material extending over 90 the body and wound upon said rollers, and means on the rollers for holding them against accidental rotation, said means comprising a pin detachably disposed through each roller and normally bearing against the inside face of the adjacent supporting member, an exteriorly screw-threaded sleeve 95 mounted upon the roller, and a nut having screw-threaded engagement with the sleeve 100 and normally bearing against the outer face of the supporting member.

5. A sharpening device of the character described comprising an elongated supporting body having supporting members at opposite ends and having a handle and extending beyond one of said supporting members, said last named supporting member having upwardly diverging slots, rollers extending through the slots of the last named supporting member, a sheet of abrading material wound upon the rollers and extending over the body, and means on the rollers for holding them from accidental rotation.

6. A sharpening device of the character described comprising an elongated supporting body having supporting members at opposite ends and having a handle and extending beyond one of said supporting members, said last named supporting member having upwardly divergent slots, rollers ex- 125

- tending through the slots of the last named supporting member, a sheet of abrading material wound upon the rollers extending over the body, and means on the rollers for holding them from accidental rotation, and consisting of a member disposed on each roller and bearing against the inside faces of the supporting member, and a nut having operative engagement with the roller and bearing against the outside face of said supporting member.
7. A sharpening device of the character described comprising an elongated supporting body having a rounded upper face and corners, one end of the supporting member being formed with an integral handle, a plate attached to the opposite end of the supporting member and extending downward below it, a plate attached to the handle end of the supporting member and extending below it and through which said handle
- passes, rollers mounted in said plates and disposed below the supporting member, an abrading sheet attached to said rollers, and means for holding said rollers against accidental rotation.
8. A sharpening device of the character described comprising a body, supporting members attached to the ends of the body, an abrading sheet extending over the body, and rollers rotatably mounted in the supporting members, each of said rollers being longitudinally grooved and transversely bored at a plurality of points, and laces threaded through the abrasive sheet and through said bores.

In testimony whereof I affix my signature in the presence of two witnesses.

CHARLES F. CRAMER.
